OIL WELL PUMP

Roy C. Williams, Wayne, Ohio

Application May 14, 1936, Serial No. 79,666

1 Claim. (Cl. 309—23)

This invention relates to pumps for oil wells or the like, and is particularly directed to the plunger and barrel elements of such a pump. It has heretofore been the practice to provide a seal against leakage of oil between the plunger and barrel of an oil well pump either by a series of resilient cups of leather, rubber, or similar material, or by grinding the plunger to fit closely in the barrel, leaving a clearance of some .002 of an inch and rely on the oil film to seal the pumps against leakage. In pumps of the latter type wear occurs between the plunger and barrel largely due to sand and other foreign substances working their way between the closely fitting surfaces and causing abrasion. The wear eventually progresses to such an extent that the oil film will no longer hold a seal between the stationary barrel and the reciprocating plunger. At this time the pump must be pulled out of the well and reground and fitted, a machining operation which can usually be performed on special equipment not available in the oil field. This means that either the well is shut down for an extended period or that a spare pump must be stocked to replace the worn one.

The primary object of the present invention is the provision of an oil sealed pump in which worn parts may be replaced, and the pump restored to its original close fitting state in the field.

Another object of the invention is the provision of readily replaceable sealing elements, the manipulation of which does not require elaborate special tools when the pump is repaired.

Other objects and advantages will be apparent from the following detailed description and from the accompanying drawing, illustrative of the invention, and in which—

Figure 1 is a fragmentary sectional view, with some parts in full, of a pump embodying the present invention; Fig. 2 is a perspective view, with a part broken away, of one of the sealing elements; Fig. 3 is a fragmentary sectional view of a modified form of working barrel, and Fig. 4 is a diagrammatic sectional view of a plunger constructed in accordance with the present invention.

The operation of a conventional deep well plunger pump actuated through a line of sucker rods is well known and will not be entered into. It will be appreciated that in most pumps of this character the stroke of the plunger is less than the length of the barrel in which it operates.

Referring to the drawing, the working barrel

the numeral 2. The plunger is adapted to be reciprocated in the usual manner by a line of sucker rods 3, and is equipped with an upper ball check valve 4 and a lower ball check valve 6.

The plunger includes a hollow central stem or mandrel 8 which, as shown in Fig. 4 is tapered, being narrower at its upper end than at its lower end. The extent of taper of the mandrel or stem may vary but is preferably about .002 of an inch in diameter for every six inches of length, the 10 mandrel in the form shown being approximately four feet long. It will be appreciated that the taper shown in the drawing is greatly exaggerated for purposes of illustration.

Fitted closely about the tapered surface of the 15 plunger stem or mandrel 8 are a plurality of resilient sleeves 10, such as shown in Fig. 2. The sleeves are preferably formed from flat spring metal or other suitable resilient material so that they are capable of expansion. The spring material is coiled in a tight helix so that the convolutions lie closely together and contribute to prevent axial movement between adjacent turns. The inner surface of each sleeve lies closely adjacent the tapered surface of the mandrel, while 20 the outer surface must necessarily be cylindrical so that there is no variation in the outer diameter of the entire plunger from top to bottom. Thus, in effect, the inner surface of each sleeve 25 is tapered conversely to the taper of the plunger 30 and the thickness of each of the series is greater at the top than at the bottom. If the taper of the stem or mandrel 8 is .002 of an inch in diameter for each six inches in length, then the variation in thickness of each sleeve will be .002 of an 35 inch from top to bottom since the sleeves are, in the form shown, approximately six inches long. It will be seen that when assembled on the plunger stem or mandrel, the series of sleeves form a 40 continuously cylindrical surface on their exterior 40 so that the plunger in use is similar to a cylindrical piston of metal. The series of sleeves 10 are held on the mandrel or stem 8 by nuts 14 at the top and bottom, the nuts being received on threaded portions 15 of the mandrel or stem. 45

When the pump has been in operation for some time, the diameter of the plunger will be reduced by reason of wear to such a point that an oil seal will no longer hold between the plunger and the adjacent working surface of the barrel. At this 50 time, the plunger may be removed from the well, the lowermost of the sleeves 10 removed, the remainder of the sleeves forced down on the mandrel and the top one renewed. It will be seen that as each of the series is forced down on the 55

mandrel, the tapered inner surface overlies a new surface substantially .002 of an inch greater in diameter and the coiled metallic sleeve is expanded so that the outside diameter is increased 5 to the original dimension, if the wear has progressed so that the outside diameter was reduced approximately .002 of an inch.

To manipulate the coiled resilient sleeve elements 10, it is necessary only to provide a simple 10 means to expand the same by uncoiling them slightly. For this reason, small holes 12 are drilled adjacent the top and bottom of each sleeve and are adapted to receive a pin on which a turning force may be exerted to uncoil the sleeve. 15 The sleeves, when uncoiled slightly, slip very readily over the tapered surface of the mandrel or stem 8 to assume their new position, replacing the next lower sleeve of the series. Thus, as the 20 wear of the plunger progresses, the top sleeve of the series will progressively replace each of the sleeves below it until it finally assumes the initial position of the lowermost sleeve, after which it is thrown away.

In the conventional pump, the stroke of the 25 plunger is considerably shorter than the length of the barrel in which it operates, so that all of the wear in the barrel is concentrated in a comparatively short length adjacent the center. In order to adapt the barrel for repeated use of the 30 plunger, the present invention provides a working portion of a smaller diameter adjacent the center of the barrel. This portion diagrammatically shown at 16 may be formed by plating the interior of the barrel to decrease the wall diameter 35 over a predetermined portion, and thus form shoulders 17 at the top and bottom of the working portion. The width of the shoulders 17 may be approximately .006 of an inch, so that they are greatly exaggerated in the drawing. It will thus 40 be seen that when wear occurs in the barrel and the plunger is renewed by moving the series of sleeves 10 downwardly to restore its original diameter, the plunger will still be able to fit in the working portion of the barrel and form a seal therewith. Obviously, the constricted working 45 portion of the barrel may be formed in any well known manner.

The present invention also contemplates the use of a plain, cylindrical plunger cooperating 50 with a working barrel lined with a series of the coiled resilient sleeve elements. As shown in Fig. 3, the working barrel is made sectional so that the center, effective portion 20 may be provided with

a liner composed of the coiled resilient sleeve elements 10. The inner surface of the section 20 will be tapered substantially as the stem or mandrel 8 was tapered in the form above-described, so that by conversely tapering the surface of the 5 series of sleeves 10, a cylindrical working barrel, which may be readily renewed, will be formed. The upper and lower sections of the barrel are preferably threaded to the center, lined section, so that when the barrel is pulled from the well, the lining members may be readily accessible to be moved down in the barrel as the wear progresses.

It will be appreciated that by forming the sleeves 10 of coiled material, the space between 15 each convolution will, in effect, form an oil channel so that the working surfaces are properly lubricated at all times.

While the invention has been described in connection with a tapered mandrel and tapered barrel of particular length and dimensions, it should be expressly understood that various modifications and changes may be made in the form and disposition of the parts and that any known means may be used to provide the necessary 20 gradations of diameter over which the coiled sleeve elements lie when in use. It should be understood that such modifications and changes are contemplated and may be readily made without departing from the invention as described in 25 the appended claim.

Having thus described my invention, what I 30 claim as new, and desire to secure by United States Letters Patent, is:

An oil well pump plunger working in cooperation 35 with a pump barrel to provide an oil seal therebetween, including a core member, a coiled resilient sleeve means on the core member inherently of less internal diameter than the external diameter of the core member and having a working 40 diameter less than the internal diameter of the pump barrel so as to provide space for the reception of a film of oil, and means carried by the core member and engaging the ends of the 45 sleeve means so as to enable removal and replacement of the sleeve means and by manipulation to provide oil channels between adjacent helices of the sleeve means to receive therein varying portions of the oil aforesaid for distribution in the space between the periphery of the sleeve 50 means and the internal walls of the pump barrel.

ROY C. WILLIAMS.
